UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

UPPER-SHAPING MACHINE.

Application filed August 20, 1925 Serial No. 51,404.

This invention relates to machines for shaping shoe upper materials over a form or last, and is herein illustrated in its application to a machine for lasting the toes of shoes. It is 5 to be understood, however, that in various novel and useful aspects the invention is not limited to toe-lasting machines.

It has been the usual practice heretofore in the manufacture of welt shoes and other 10 kinds of shoes to last the toes in machines having toe-embracing wipers which are operated manually to wipe the upper heightwise of the toe and to wipe its margin inwardly over the bottom of the last, i. e., to 15 upwipe and to overwipe the upper. In a well known type of bed lasting machine, for example, there is provided treadle operated means for raising the wipers to upwipe the upper and for thereafter lowering them to 20 press the margin of the upper down upon the insole on the bottom of the last, and separately operated means comprising a hand lever for advancing and closing the wipers about the toe in the upwiping operation and 25 for subsequently effecting the overwiping of the margin of the upper. The operator thus has complete control at all times of the lasting operation, so that he is afforded ample opportunity to arrange the pleats or folds 30 in the margin of the upper as conditions may require and is also enabled to vary the pressure applied to the upper at different stages of the lasting operation in accordance with what he observes to be the characteristics and 35 requirements of the particular upper under treatment. The labor involved in the operation of such a machine, however, frequently imposes a substantial limitation upon the output of the machine, and the quality of the 40 work also sometimes suffers because of fatigue of the operator.

It is an object of the present invention to provide a machine having the advantages of prior machines of the type above mentioned but relieving the operator of the greater part 45 of the physical strain involved in the operation of such machines. The invention, in one aspect, accordingly provides a novel organization including independently controllable power means for effecting respectively relative movement of the shoe and the wipers heightwise of the shoe and relative overwiping movement of the shoe and the wipers. In 50 the machine herein shown independently controlled power-operated mechanisms are pro-

vided for effecting respectively wiper advancing and closing movement and movement of the wipers heightwise of the toe, each of said mechanisms comprising a friction clutch whereby the operator is enabled to start, stop 60 or reverse the movement at will and also, by varying the force of engagement of the clutch members, to vary the pressure applied to the work by the wipers. The operator thus has complete control at all times of the lasting 65 operation, as in the use of prior manually operated machines, both in respect to the time of the different wiper movements and in respect to the pressure applied in upwiping, overwiping and pressing the margin of the 70 upper down upon the insole, while at the same time being relieved of the physical strain incidental to manual operation of the wipers.

The above and other features of the invention, including also novel wiper-advancing 75 and closing means and various novel details of construction and combinations of parts, will now be more particularly described by reference to the accompanying drawings and pointed out in the claims. 80

In the drawings,

Fig. 1 is a view in front elevation of a machine in which the invention is embodied;

Fig. 2 is a plan view of the machine;

Fig. 3 is a right-hand end elevation with 85 parts broken away;

Fig. 4 is a plan view, with parts broken away, of a portion of the operating means shown in Fig. 3;

Fig. 5 is a cross-sectional view on the line 90 5-5 of Fig. 2 of portions of the machine, with other portions shown in elevation;

Fig. 6 is a view showing certain parts in section on the line 6-6 of Figs. 1 and 2;

Fig. 7 is a view of the toe wipers and their 95 operating means partly in horizontal section and partly in plan, with the cover plate over the wipers removed;

Fig. 8 is a section on the line 8-8 of Fig. 2;

Fig. 9 is a perspective view of means provided for locking the toe rest; 100

Fig. 10 is a longitudinal section through a last and shoe illustrating the manner of positioning the shoe for the operation of the wipers, and

Fig. 11 is a transverse section through the last and shoe and the shoe-positioning means and wipers.

The machine is provided with toe-embracing wipers 12 having wiping edges shaped as 110

usual in toe-lasting machines to conform substantially to the contour of the toe when the wipers are closed about the toe at the edge of the shoe bottom, these wipers being detachably secured to wiper holders 14 which are guided in a wiper carrier 16 for swinging movements about an axis located substantially at the meeting point of the wiping edges of the wipers. The wiper holders 14 are provided with rack teeth engaged by pinions 18 which are mounted in the wiper carrier 16 and are operated by a rack member 20 to impart closing and opening movements to the wipers. The wiper carrier 16 is provided with trunnions 22 which are mounted in upwardly extending arms of a lever 24 (Fig. 1) pivoted at 26 on the frame of the machine, so that by swinging movements of the lever the wiper carrier and the wipers are advanced and retracted bodily lengthwise of the shoe. Near its front end the wiper carrier 16 is pivotally supported on the upper end of a link 28, operated as hereinafter described, whereby the wipers are moved upwardly to upwipe the upper about the toe to the edge of the shoe bottom and are later moved downwardly to bring increased pressure to bear upon the margin of the upper over the bottom of the insole. Secured to the lever 24 is an arm 30 by which the lever is operated through a link 32 and mechanism to be hereinafter described.

For operating the rack member 20 (Fig. 7) to impart closing and opening movements to the wipers there is provided a plunger 34 having a reduced end portion which is slidably mounted in a recess 36 formed in a member 38. The member 38 is connected at one end to the rack member 20 and is slidably mounted for lengthwise movement in a recess formed in the wiper carrier 16. Splined on the reduced end portion of the plunger 34 is a bushing 40 which is threaded within a recess formed in the member 38 and provides an abutment for one end of a spring 42. The other end of the spring 42 abuts against a flange 44 which is a part of the plunger 34, and this flange seats against the end of a bushing 46 which is threaded in the end of the member 38. The plunger 34 is also formed with an enlarged portion 48 which is slidable within the bushing 46, and abutting against the outer end of this portion of the plunger is a collar 50 which is engaged by a member 52 slidably mounted on the plunger. It will thus be seen that the member 52 acts through the collar 50, the plunger 34 and the spring 42 to impart operative movement to the member 38 and the rack member 20 and thus to close the wipers about the toe. As the wipers are thus closed the spring 42 may yield more or less in response to resistance of the shoe, resulting in movement of the plunger 34 relatively to the member 38, and may thereafter yield further to permit open-

ing of the wipers independently of the plunger as wider portions of the toe are encountered during the unwiping movement of the wipers. It is desirable that positive means be provided for finally pressing the wipers inwardly against the upper materials in the overwiping operation, and for this purpose the enlarged portion 48 of the plunger 34 has threaded adjustably thereon a nut 54, together with a lock nut 56, for engaging the bushing 46 in the end of the member 38 and thereby imparting operative movement positively to the member 38 and the rack member 20.

For operating the member 52 there is threaded on this member a sleeve 58 connected by links 60 to upwardly extending arms of a lever 62 which is pivoted at 64 on the frame and is connected at its lower end by a link 66 to the lower end of the lever 24 by which the wiper carrier 16 is moved bodily lengthwise of the shoe. It will thus be seen that the lever 24 acts both to advance the wipers bodily and at the same time to close them inward laterally of the toe, the lever 62 being so constructed and arranged in relation to the lever 24 as to impart to the wiper-closing member 38 movement relatively to the wiper carrier 16 during the advancing movement of the wiper carrier in the same direction. As shown in Fig. 1, the link 66 is adjustably connected to the lever 62 in such manner as to permit a variation of the extent of closing movement of the wipers for a given extent of advancing movement, as may be desirable for wide variations in the shapes of toes, for example as between pointed toes and widely rounded toes.

It is desirable, for example where the same wipers are used to operate on shoes of different sizes, to adjust the wipers toward or from each other about the axis of their closing movements, so that the edges of the wipers at the beginning of the operation will be at the same distance from the sides of one size of toe that they are from the sides of another size. For this purpose the machine is provided with means for turning the member 52 within the sleeve 58 which, as above explained, is rigidly connected to the operating mechanism, this means comprising a hand wheel 68 mounted to turn on the plunger 34 and connected to the member 52 through an intermediate sleeve member 70 which is also mounted to turn on the plunger and is coupled at its opposite ends to the hub of the wheel 68 and to the member 52. The sleeve 70 is formed to serve as a worm gear for a purpose which will be hereinafter explained. Between the hand wheel 68 and a small hand wheel 72 which is fast on the end of the plunger 34 is a spring 74 which serves both to hold the members 68, 70 and 52 in assembled relation and also as a connection between the operating member 52 and the plunger 34 when the operating member is 130

5 moved in the direction to open the wipers. It will be seen that when the hand wheel 68 is turned, movement of the member 52 relatively to the member 58 in either direction serves to
 10 6 move the plunger 34 and the wiper closing member 38 in the same direction and thereby to adjust the wipers about the axis of their closing movement. It will also be seen that the spring 74 affords provision for yield be-
 15 10 between the operating member 52 and the plunger 34 in the opening of the wipers, as a measure of safety in case the operating mechanism should continue its movement after the wiper carriers 14 have been moved into abut-
 20 15 ting relation to each other. By manipulation of the small hand wheel 72 the plunger 34 may be turned to adjust the threaded member 40 along the member 38 and thus to vary the degree of compression of the spring 42, thereby
 25 20 rendering the wipers more or less yieldable in response to resistance of the shoe, as may be desirable for different grades of shoe upper materials.

25 Various features of the wiper-operating means thus far described are claimed in my copending application, Serial No. 83,372, filed on January 23, 1926.

30 The machine is further provided with means for assisting the operator in adjusting the wipers for different sizes of shoes by indicating the proper adjustments for different sizes. For this purpose there is provided a casting 76 having lugs 78 and 80 which are sleeved respectively on the hub of the wheel 68 and on one end of the member 52, these lugs being extended below the plunger 34 and having mounted therein a rod 82 which is fast at one end in a lug 84 which extends downwardly from the member 58. The casting 76 is thus held from turning about the axis of the plunger 34 and is movable with the member 52 in directions lengthwise of the plunger. Mounted in the casting 76 is a worm gear 86 which is operatively connected to the worm member 70 and is fast on a shaft 88 which also carries an indicator wheel 90. Adjacent to this wheel is an arc-shaped cover 92 provided with a slot 94 over the periphery of the wheel and having at the side of the wheel a pointer 96. The cover 92 is slotted at the side of the wheel 90, as shown in Fig. 1, so that it may be adjusted about the axis of the wheel, and it is held in adjusted position by means of a clamping screw 98 threaded in a part of the casting 76. At the side of the wheel 90, on a portion of the casting 76, there may be secured a card or other member bearing a series of width indications or letters opposite to the pointer 96, as illustrated in Fig. 1, and on the periphery of the wheel there may be provided, by means of a detachable strip of material or otherwise, a plurality of size numerals, as illustrated in Fig. 2. It will be seen that as the wheel 90 is turned simultaneously with the adjustment of the wipers by the hand

wheel 68 different size numerals will appear through the slot 94 in the cover 92. In the use of this device the cover 92 will first be adjusted to bring the pointer 96 opposite to that letter which indicates the width of shoe upon 70 which the machine is to operate, and thereafter the hand wheel 68 will be turned to adjust the wipers until there appears through the slot 94 the numeral which indicates the size of the shoe. It will be understood that 75 the distances between the different width letters and between the different size numerals will be so calculated that the correct adjustment of the wipers for any particular size and width of shoe will be properly indicated. 80

For positioning the shoe the machine herein shown is provided with a toe rest 100 and a hold-down arm 102 between which the forepart of the shoe is clamped as illustrated in Figs. 10 and 11. The arm 102 has fast there- 85 on a plate 104 provided with three pins 106 positioned in predetermined relation to the wipers and arranged to extend through holes in the insole and into holes in the last formed in predetermined relation to the contour of 90 the insole and of the last respectively. This method of positioning the last and its shoe materials, and the means utilized, are fully described and are claimed in Letters Patent No. 1,674,060, granted upon my application on 95 June 19, 1928. It will be understood that in this manner the shoe is positioned lengthwise, laterally and angularly in proper relation to the wipers, so that after the wipers have been properly adjusted by manipulation of the 100 hand wheel 68, they will conform to the contour of the toe when they have been advanced and closed a predetermined distance, and so that the proper relation is insured between the bottom of the forepart of the shoe and the 105 plane of the wipers for the best results in the overwiping operation. It will be recognized, however, that while this means for positioning the shoe has important advantages, since it eliminates the necessity of providing means 110 for adjustably tipping the wipers lengthwise and laterally of the shoe and insures that the shoe will be properly positioned for the most effective action of the wipers thereon without the need for any particular care or skill on the part of the operator, the present invention in many of its aspects is not limited to the use of the particular shoe-positioning means herein shown. 115

120 The toe rest member 100 is mounted on the upper end of a rod 108 which is movable downwardly against the resistance of a spring 110, and the hold-down arm 102 likewise is mounted on a vertically movable plunger 112 and carries a rod 114 which is guided in a por- 125 tion of the frame of the machine to prevent turning movement of the plunger. Guided for vertical movement below the plunger 112 is a rod 116 which is connected to the plunger 130 by a coupling member 118. Fast on the rod

116 is a collar 120 which provides an abutment for the lower end of a spring 122 within a housing 124, the upper end of the spring being seated within a recess in a sleeve member 126 which is slidable for a limited distance vertically on the rod 116 between the upper end of the housing member 124 and the lower end of the coupling member 118. The member 126 is connected by links 128 to a lever 130 which is mounted to swing about a shaft 132 and is provided with an arm 134 having a roll 136 in engagement with a cam 138 on a shaft 140. A spring 142 acts on the lever 130 to lift the plunger 112 and the holdown arm 102 as permitted by the cam 138 and to maintain the roll 136 in engagement with the cam.

The shaft 140 has fast thereon a gear wheel 144 which is engaged and operated by a smaller gear wheel 146 mounted to turn on the shaft 132. The shaft 132 is coupled to the end of a main operating shaft 148 (Fig. 2) which is driven continuously by a belt pulley 150. Fast on the end of the shaft 132 is a clutch member 152, and a co-operating clutch member 154 is mounted to slide lengthwise of the shaft 132 into and out of operative engagement with the member 152 and is connected by a pin 156 to the pinion 146 to turn with the pinion. Springs 158 move the clutch member 154 into engagement with the member 152 when permitted by a clutch controlling lever 160 which has a wedge face for disconnecting the clutch members in a well known way, as illustrated in Fig. 4. The lever 160 is connected by a crank arm 162 and a link 164 to a treadle lever 166. After the shoe has been mounted on the pins 106 the operator depresses the treadle lever 166 and thereby renders the clutch 152, 154 effective to operate the gear wheel 144 and the cam 138, whereupon the cam imparts downward movement to the holdown arm 102 to clamp the shoe upon the toe rest 100 and to depress the toe rest. The operator releases the treadle in time to cause the clutch members to be disconnected from each other at the end of a single revolution of the gear wheel 146, the treadle being returned by a spring 168. The parts are thus brought to a stop with the cam 138 in position to maintain the holdown arm 102 at the lower limit of its movement. In order to insure that the parts will be stopped in the right position, a spring arm 170 is arranged to bear on the periphery of the clutch member 154 and to act as a brake in co-operation with a lug 172 on the periphery of the clutch member.

To hold the toe rest 100 against subsequent downward movement under the pressure of the wipers on the shoe, there is provided locking means (Figs. 3 and 9) comprising a plurality of pawls 174, herein shown as four in number, arranged in staggered relation for engagement with downwardly facing ratchet teeth 176 formed on a member which is fast on

the rod 108. Springs 178 act, when permitted, to force the pawls into engagement with the ratchet teeth, and the pawls are forced out of engagement with the ratchet teeth by movement of rods 180 which carry collars 182 for engagement with the pawls. Springs 184 tend to elevate the rods 180 and thus to render the springs 178 effective to move the pawls into engagement with the ratchet teeth. The rods 180 are controlled by a lever 186 which engages collars fast on the rods and is provided with a roll 188 in engagement with a cam 190 on the shaft 140. When the shaft 140 and the cam 138 have been turned far enough to move the holdown arm 102 substantially to its lower limit of movement, the cam 190 releases the lever 186 to such an extent as to permit the pawls 174 to engage the ratchet teeth. Such slight further movement of the cam 138 as may occur after the toe rest has been locked against further downward movement results in compression of the spring 122 in the holdown operating connections.

For imparting to the wipers movements heightwise of the toe and advancing and closing movements through the respective link members 28 and 32 hereinbefore referred to, the machine is provided with separately controlled friction clutch mechanisms. The continuously running shaft 148 carries a pinion 192 (Figs. 2 and 5) which engages and drives continuously pinions 194 and 196 mounted to turn idly on shafts 198 and 200. The pinions 194 and 196 have fast thereon friction clutch disks 202 and 204. The shaft 148 also carries a pinion 206 (Fig. 6), which through idle gears 208 and 210 drives pinions 212 and 214 mounted to turn on the shafts 198 and 200. The pinions 212 and 214 have fast thereon friction clutch disks 216, 218. It will thus be seen that on the shaft 198 there are oppositely facing clutch disks 202 and 216 which are driven respectively in opposite directions, and that on the shaft 200 there are oppositely facing clutch disks 204 and 218 which are also driven respectively in opposite directions.

The shaft 198 has fast thereon a worm 220 which engages a segmental worm gear 222 mounted fast on a shaft 224, and the shaft 224 has fast thereon an arm 226 to which the link 28 is connected. It will thus be seen that when the worm 220 is turned in one direction it operates through the members 222, 226 and 28 to raise the wiper carrier 16 and the wipers, and that when it is turned in the opposite direction it operates to lower the wipers.

Between the two oppositely facing clutch disks 202 and 216 on the shaft 198 there is splined on the shaft a clutch member 228 having thereon friction clutch disks 230 and 232 facing the disks 202 and 216 respectively. The clutch member 228 is controlled by

a yoke member 234 which is carried by a rock shaft 236, and fast on this rock shaft is an arm 238 connected by a link 240 to an arm 242 on a rock shaft 244 which has thereon a double acting treadle 246. By depressing the left-hand end of the treadle 246 (Fig. 1) the operator may move the clutch disk 230 into engagement with the disk 216 and thereby cause the wipers to be raised by power 10 to upwipe the upper, and by depressing the right-hand end of the treadle he may move the disk 230 into engagement with the disk 202 to cause the wipers to be moved downwardly either to increase their pressure upon 15 the overwiped upper materials or to return them to their lower limit of movement.

To maintain the clutch member 228 normally out of engagement with the members 202 and 216, the shaft 244 has thereon a bracket 248 provided on opposite sides of the shaft respectively with spring plungers 250 and 252 which engage the base plate of the machine and serve to maintain the treadle 246 and the connected parts in an intermediate idle position. The machine is further provided with means for insuring against excess movement of the wipers in either direction, to avoid possible breakage of parts, especially in case the wipers are operated in the absence of a shoe. For this purpose the shaft 224 has fast thereon a pair of arms 254 which carry adjustable screws 256 arranged for engagement with opposite sides of an extension of the arm 238 to which the treadle 246 is connected. It will thus be seen that if the treadle is held depressed too long in either direction, the corresponding screw 256 will engage the arm 238 and disconnect the clutch member 228 from the clutch member which is driving it.

For imparting to the wipers advancing and closing movements, and retracting and opening movements, through the link 32 and the parts hereinbefore described, the shaft 200 has fast thereon a worm 258 which engages a segmental worm gear 260 fast on a rock shaft 262, this rock shaft having thereon an arm 264 connected to the link 32. As hereinbefore described, there are mounted to turn on the shaft 200 oppositely facing clutch disks 204 and 218 which are driven respectively in opposite directions. Between these clutch disks there is splined on the shaft 200 a clutch member 266 (Figs. 1 and 6) provided with clutch disks 268 and 270 facing the respective clutch disks 204 and 218. The clutch member 266 is controlled by a yoke member 272 which is fast on a vertical rock shaft 274 provided at its upper end with a hand lever 276. When the operator moves this hand lever toward him, as he stands in working position, the clutch disk 268 is moved into engagement with the clutch disk 204, whereupon the worm 258 is rotated in the direction to effect the advancing and

closing movements of the wipers. If the hand lever is moved in the opposite direction, the clutch members 270 and 218 are rendered effective to retract and open the wipers. To maintain the clutch member 266 and the hand lever 276 normally in an intermediate idle position, there is secured on the lower end of the shaft 274 a bracket 278 provided at opposite sides of the shaft with spring plungers 280 which engage a member 282 75 on the frame.

The machine is further provided with means for preventing excess movement of the wipers as they are advanced and closed or as they are opened and retracted. To this end, there is fast on the rock shaft 262 an arm 284 (Figs. 1 and 5) to which is connected a rod 286 slidably mounted in a member 288 pivot- 80 ed to an arm 290 (Fig. 6) projecting from the yoke member 272. Fast on the rod 286 are stops 292 for engaging the member 288 on opposite sides respectively and thereby turning the yoke member 272 to move the clutch member 266 to an idle position in case movement of the wipers is continued too long in 90 either direction.

In the operation of the machine, a shoe is mounted on the pins 106 in the manner described, and the treadle 166 is then momentarily depressed to release the clutch member 154 and cause the shoe to be clamped on the toe rest 100 and to be moved downwardly to the position predetermined by the operating mechanism, the toe rest being then locked by the pawls 174 against further downward 100 movement. By manipulation of the treadle 246 and the hand lever 276 in proper relation to each other the operator then causes the wipers to advance and close about the toe and to wipe the upper up to the edge of the 105 shoe bottom, and thereafter to wipe the upper inwardly over the insole and to bring increased downward pressure to bear upon the overwiped upper. It will be understood that the operator may at any time stop any of the 110 movements of the wipers and likewise reverse the movement at will and repeat any part of the wiping operation, and that he thus has as effective control of the wipers as if they were operated manually, but without the labor incidental to manual operation. Furthermore, the friction clutch members utilized are of a type permitting relative slipping movement between them in response to resistance of the work, and a further important advantage in 115 the use of the machine accordingly is that the operator is enabled to control the amount of pressure applied to the shoe, in upwiping, overwiping or pressing downwardly upon the shoe, since these pressures will depend upon 120 the forces applied to the hand lever 276 and the treadle 246.

After the upper has been wiped satisfactorily into lasted position, it is fastened in the usual way, for example by the application 130

of a toe binder in the case of welt shoe work, or by driving the lasting tacks in the case of McKay shoe work, and thereafter the treadle 166 is again momentarily depressed to cause the shaft 140 to continue its movement to starting position and release the shoe.

Having described the invention, what I claim as new and desire to secure by Letters Patent of the United States is:

10. 1. In a machine of the class described, the combination with shoe-positioning means and toe-embracing wipers relatively movable to upwipe and to overwipe the toe of an upper, of power-operated means for effecting the relative upwiping and overwiping movements comprising a power-driven shaft and independently controlled mechanisms operated thereby for starting or stopping the relative upwiping movement or the relative overwiping movement, each independently of the other, at the will of the operator. 70
15. 2. In a machine of the class described, the combination with shoe-positioning means and toe-embracing wipers relatively movable heightwise of the shoe to upwipe the toe of an upper and to press its margin down upon the insole, of power-operated means for effecting the relative upwiping and pressing movements and for also operating the wipers to wipe the upper inwardly over the insole comprising a power-driven shaft and independently controlled mechanisms operated thereby for starting, stopping or reversing the relative upwiping or pressing movement and for independently starting, stopping or reversing the overwiping movement, at the will of the operator. 85
20. 3. In a machine of the class described, the combination with shoe-positioning means and end-embracing wipers relatively movable heightwise of the shoe to press the margin of the upper upon the insole, of power-operated means for effecting the relative pressing movement of the shoe and the wipers and for also operating the wipers to wipe the upper inwardly over the insole comprising a power-driven shaft and independently controlled mechanisms operated thereby for effecting respectively the relative pressing movement and the overwiping movement. 95
25. 4. In a machine of the class described, the combination with shoe-positioning means and end-embracing wipers, of a power-driven shaft, mechanisms operated by said power shaft for imparting respectively to the wipers movement heightwise of the shoe and movement inwardly over the bottom of the last, and devices enabling the operator to control each of said mechanisms independently of the other to start or stop at will the movement effected by that mechanism. 105
30. 5. In a machine of the class described, the combination with shoe-positioning means and toe-embracing wipers relatively movable to upwipe and to overwipe the toe of an upper, of independently controlled power-operated mechanisms for effecting respectively the relative upwiping and overwiping movements, each of said mechanisms comprising a friction clutch and controlling means enabling the operator at will to start or to stop the relative movement effected by that mechanism and also to vary the pressure applied to the work by that mechanism. 110
35. 6. In a machine of the class described, the combination with shoe-positioning means and toe-embracing wipers relatively movable to upwipe and to overwipe the toe of an upper, of independently controlled power-operated mechanisms for effecting respectively the relative upwiping and overwiping movements, each of said mechanisms comprising a double-acting friction clutch and controlling means enabling the operator at will to start, stop or reverse the relative movement effected by that mechanism. 115
40. 7. In a machine of the class described, the combination with shoe-positioning means and toe-embracing wipers relatively movable to upwipe and to overwipe the toe of an upper, of different power-operated mechanisms for effecting respectively the relative upwiping and overwiping movements, each of said mechanisms comprising a friction clutch controllable during the wiping operation to vary the pressure applied to the work by that mechanism, and separate manually operated members for controlling the respective clutches each independently of the other. 120
45. 8. In a machine of the class described, the combination with shoe-positioning means, of toe-embracing wipers movable to upwipe and to overwipe the toe of an upper, and independently controlled power-operated mechanisms for effecting respectively the upwiping and overwiping movements of the wipers, each of said mechanisms comprising a friction clutch controllable by the operator to start or to stop at will the movement of the wipers effected by that mechanism, and worm gearing connecting said clutch to the wipers and operative automatically to retain the wipers in any position to which they are moved. 125
50. 9. In a machine of the class described, the combination with shoe-positioning means and toe-embracing wipers, of power-operated mechanism for effecting relative movements of said shoe-positioning means and the wipers to upwipe the toe of an upper and thereafter to press down the margin of the upper over the bottom of the last, said mechanism comprising a friction clutch and controlling means for starting, stopping or reversing the relative movement at the will of the operator, and independently controlled friction clutch mechanism for advancing and closing the wipers at the will of the operator. 130
55. 10. In a machine of the class described, the combination with shoe-positioning means

and end-embracing wipers, of independently controlled power-operated mechanisms for imparting respectively to said wipers overwiping movement and upper pressing movement, each of said mechanisms comprising a friction clutch controllable during the operation of the wipers to vary the pressure applied to the work by that mechanism.

11. In a machine of the class described, the combination with shoe-positioning means and end-embracing wipers, of independently controlled power-operated mechanisms for effecting respectively advancing and closing movement of the wipers and relative movement of the shoe and the wipers heightwise of the shoe, each of said mechanisms comprising a friction clutch and controlling means enabling the operator to start or to stop at will the movement effected by that mechanism and also to vary the pressure applied to the work by the wipers at any time in the lasting operation.

12. In a machine of the class described, the combination with shoe-positioning means and toe-embracing wipers, of power-operated mechanism for effecting relative movement of said shoe-positioning means and the wipers heightwise of the toe to upwipe the upper and thereafter to press its margin down over the bottom of the last, said mechanism comprising a friction clutch and controlling means enabling the operator to start or stop the relative movement at will and also to vary the pressure applied to the margin of the upper by the wipers, and an independently controlled friction clutch mechanism for advancing and closing the wipers with pressure variably determined by the operator both in the upwiping operation and in the subsequent wiping of its margin over the bottom of the last.

13. In a machine of the class described, the combination with shoe-positioning means and toe-embracing wipers, of independently controlled clutch mechanisms for imparting respectively to said wipers overwiping movement and upwiping and pressing movements, a hand lever for controlling the overwiping clutch mechanism, and a treadle for controlling the other clutch mechanism.

14. In a machine of the class described, the combination with shoe-positioning means, of toe-embracing wipers movable to upwipe and to overwipe the toe of an upper, worms connected to the wipers for effecting respectively the upwiping movement and the overwiping movement, double acting clutches associated respectively with the different worms and adapted to start, stop or reverse the movements of the worms each independently of the other at any time, and separate manually operated members for controlling the respective clutches to enable the operator to determine throughout the toe-lasting opera-

tion the position of the wipers heightwise and lengthwise of the toe.

15. In a machine of the class described, the combination with shoe-positioning means, of toe-embracing wipers movable to upwipe and to overwipe the toe of an upper, and independently controlled power-operated clutch mechanisms for effecting respectively the upwiping movement and the overwiping movement of the wipers and for starting or stopping either movement at the will of the operator.

16. In a machine of the class described, the combination with shoe-positioning means and toe-embracing wipers, of mechanism for effecting relative movement of said shoe-positioning means and the wipers to upwipe the toe of an upper, and independently controlled power-operated means for advancing and closing the wipers comprising a friction clutch manually controllable in the lasting operation to vary the pressure applied to the work by the wipers.

17. In a machine of the class described, the combination with shoe-positioning means and end-embracing wipers, of power-operated mechanism for advancing and closing said wipers comprising a double acting friction clutch and controlling means enabling the operator at will to start, stop or reverse the movement of the wipers.

18. In a machine of the class described, the combination with shoe-positioning means and end-embracing wipers, of power-operated mechanism for advancing and closing said wipers comprising a clutch controllable by the operator to start or to stop the movement of the wipers at will, and worm gearing connecting said clutch to the wipers and operative automatically to retain the wipers in any position to which they are moved.

19. In a machine of the class described, the combination with shoe-positioning means and end-embracing wipers mounted for relative movement heightwise of the shoe and also for relative movement to wipe the margin of the upper inwardly over the shoe bottom, of operating means comprising a power-driven shaft and independently controlled mechanisms operated thereby for effecting said different relative movements each independently of the other.

20. In a machine of the class described, the combination with shoe-positioning means and end-embracing wipers mounted for relative movement heightwise of the shoe and also for relative movement to wipe the margin of the upper inwardly over the shoe bottom, of operating means comprising a power-driven shaft and independently controlled mechanisms operated thereby for starting, stopping or reversing said different relative movements, each independently of the other, at the will of the operator.

21. In a machine of the class described, the combination with shoe-positioning means and end-embracing wipers mounted for relative movement heightwise of the shoe and also for relative movement to wipe the margin of the upper inwardly over the shoe bottom, of power-driven operating means comprising independently controlled clutches for effecting and controlling said different relative movements each independently of the other. 10
22. In a machine of the class described, the combination with shoe-positioning means and end-embracing wipers mounted for relative movement heightwise of the shoe and also for relative movement to wipe the margin of the upper inwardly over the shoe bottom, of power-driven means comprising a friction clutch for effecting said relative heightwise movement and for stopping said movement at 15
- the will of the operator, and independently controlled power-operated means for effecting the relative overwiping movement. 20
23. In a machine of the class described, the combination with shoe-positioning means and end-embracing wipers mounted for relative movement heightwise of the shoe and also for relative movement to wipe the margin of the upper inwardly over the shoe bottom, of power-driven means comprising a friction clutch for effecting said relative overwiping movement and for stopping said movement at the will of the operator, and independently controlled power-operated means for effecting the relative heightwise movement. 25
